CLAIM

The ornamental design for an ultrasound imaging assembly, as shown and described.

DESCRIPTION

FIG. 1 is a front perspective of an embodiment of an ultrasound imaging assembly showing our new design;

FIG. 2 is a bottom perspective view thereof;

FIG. 3 is a rear elevation view thereof;

FIG. 4 is a front elevation view thereof;

FIG. 5 is a side elevation view thereof;

FIG. 6 is a side elevation view thereof;

FIG. 7 is a top plan view thereof; and,

FIG. 8 is a bottom plan view thereof.

Any broken lines immediately adjacent the shaded areas represent the bounds of the claimed design, while all other broken lines are directed to environment and are for illustrative purposes only; broken lines form no part of the claimed design.
